UNITED STATES PATENT OFFICE.

FRANCIS FERDINAND MOLLOY, OF MONTREAL, QUEBEC, CANADA.

VENDING MACHINE.

Application filed September 15, 1921. Serial No. 500,902.

To all whom it may concern:

Be it known that I, FRANCIS F. MOLLOY, a citizen of the United States, and a resident of Montreal, Province of Quebec, Canada, have invented a new and Improved Vending Machine, of which the following is a full, clear, and exact description.

This invention relates to a vending machine, and has for an object the provision of a simply operated, economically manufactured, and strong device adapted for the vending of any desired articles, in which the operation depends upon the insertion of coins and the manipulation of a handle by the operator.

Another object resides in the provision of means whereby the handle cannot be effectively operated unless the proper number of coins have been inserted.

A further object resides in the provision of means whereby the coin-controlled mechanism is simple and efficient and constructed so that the coins form part of the means for permitting the effective operation of the handle.

A still further object resides in the provision of means whereby the articles to be vended may, one at a time, be ejected from their containers in a simple and efficient manner.

Another object resides in the provision of means whereby only a predetermined number of articles can be ejected upon the insertion of a definite amount of money.

A further object resides in the particular construction and arrangement of parts which are hereinafter described and claimed and shown in the accompanying drawings.

The invention is illustrated in the drawings, of which—

Figure 1 is a vertical section taken on the line 1—1 of Figure 3;

Figure 2 is a partial vertical section similar to the lower half of Figure 1, showing the operating parts in another position;

Figure 3 is a horizontal section taken on the line 3—3 of Figure 2;

Figures 4 and 5 are partial vertical sections somewhat enlarged, taken on Figure 6 and showing the parts in different operative positions;

Figure 6 is a section taken on the line 6—6 of Figure 5;

Figure 7 is a partial, enlarged front ele-

vation of the coin-controlled chutes showing 55 the coin and the operating levers in one position;

Figure 8 is a similar view showing the parts in another position;

Figure 9 is a horizontal section taken 60 through one of the coin chutes;

Figure 10 is a front elevation of a group of members forming the coin-controlling means; and

Figures 11 and 12 are separate views of 65 two of the plates forming part of said means.

Coin-controlling mechanism.

The invention as set forth in the drawings comprises a coin-controlling mechanism. 70 This mechanism is mounted in any suitable casing 1 the front face of which is provided with a plurality of slots, such as 2. These slots are provided to permit of the extension therethrough of a handle 3 which is pivoted within the machine on a suitable shaft 4. Within the casing this handle portion is formed into two blade portions 5 and 6 each of which is pivoted to the shaft 4, as above mentioned. Each of the blade portions 5 and 6 is preferably, although not necessarily, formed with a T cross section, as shown in Figures 7 and 8. The handle 3 is adapted to be moved downwardly from the position shown in Fig. 1 to the position shown in 85 Fig. 2. During this movement each of the blades 5 and 6 are adapted to move downward between coin guide plates, to be hereinafter described. These guide plates form a coin chute. Each coin chute comprises a pair of frame members. Each frame member comprises three plates 7, 8 and 9 which extend from a shelf or platform 10 to a point beneath the front portion of the casing 1, adjacent the handle portion 3 in its normal position. The upper end of each of these plates 7, 8 and 9 is suitably connected rigidly to bracket portions, such as 11. The lower ends of the plates are connected by brackets, such as 12, to the platform 10. 100 Each of these plates 7, 8 and 9 are spaced apart and are adapted to receive therebetween flexible plates, such as 13 and 14. The flexible plate 13 is disposed between the frame plates 7 and 8, and the flexible plate 14 is disposed between the frame plates 8 and 9. These flexible plates 13 and 14 are connected by any suitable means, such as

85

90

95

100

105

rivets 15, at their upper ends with the plates 7, 8 and 9, and are also connected to the frame plates at their lower ends, although the flexible plates are provided with slots 16 through which the lower rivets 17 are adapted to pass in order to permit of a certain movement of the lower ends of these flexible plates 13 and 14, as hereinafter mentioned. The outer lateral faces, such as 18, of the plates 13 and 14 are connected by rivets, such as 19, so that when one of these plates is moved the other one moves with it.

On the inner face of each of the plates 13 is a curved cam surface, such as 20, and on the inner face of the flexible plate 14 is a projecting or latch portion 21. The flexible plates 13 and 14 are so disposed with respect to the frame plates 7, 8 and 9 that throughout substantially their entire length their inner edges are spaced rearwardly from the inner edges of the frame plates 7, 8 and 9, so as to form slots or grooves through which a coin 22 may pass. It will be understood, therefore, that each of the blades 5 and 6 of each handle portion 3 extends downwardly in its movement past a group comprising a pair or sets of plates, as above mentioned and as particularly shown in Figs. 7, 8 and 9.

In Fig. 7 a coin 22 is shown in position extending between two opposite plates 13 of a group with its edges bearing against the cam surface 20 of these plates. This coin was inserted in a chute, such as 23, which extends slightly above the top of the casing 1 and leads to a point near the upper end of the sets or group of plates forming the guideways or chutes for the further travel of the coin, as above mentioned. The chutes 23 are off set from the direct line of the sets of plates 7, 8 and 9 to permit of the movement of the blades 5 and 6. From an examination of Figs. 7 and 8, it will be seen, therefore, that the blades 5 and 6 as they are moved downwardly by the movement of the handle 3 will contact with the upper edge of the coin. Blade 5 will contact with one coin, and blade 6 will contact with another coin in an adjacent chute. The main body of the T section of each blade will contact with the coin first. Furthermore, movement of the coin from the position shown in Fig. 7 will cause the flexible plates 13, by reason of the engagement of the coin with the cam surface 20, to be forced backward. This movement will also cause the movement of plates 14 backward also, by reason of the guiding connection between the plates 13 and 14. The backward movement of plates 14 will cause the withdrawal of the projections 21 out of the line of the horizontal portion of the T section of each blade, so that the blades can be moved down to the lower end of their stroke.

It will be readily observed that if a coin is not interposed in the chute before the blade is moved down, there will be no means to withdraw the flexible plates and that, consequently, the projections 21 will extend beneath the path of movement of the T section and prevent more than a certain amount of movement thereof. The permissible distance of movement of the blades before they are stopped by the projection 21 is, of course, gauged to be such that the article being vended will not be ejected during this movement. It will be understood, therefore, why the lower ends of the flexible plates are provided with slots 16. This provision is made so that when they are bent outwardly the lower ends can move slightly with respect to the rivets or pins 17. After the coin has been forced down past the position shown in Fig. 8, it will drop by gravity into any suitable receptacle, such as 24, disposed beneath the coin guides or chutes and suitably attached to the platform 10.

Article ejecting apparatus.

Extending across between the blades 5 and 6 of each handle portion 3 is a bar 25. To this bar 25 a link 26 is connected. The other end of the link 26 is connected to a portion 27 of a bell crank lever mounted loosely on a shaft 28, and the other end 29 of which lever is connected to a link 30. This link 30 is in turn connected to one member 31 of a bell crank lever loosely pivoted on shaft 4 and connected by a sleeve 32 to the blade members 5 and 6. The other member 33 of the bell crank lever is connected by a link 34 to an ejecting member or casing 35. This casing 35 is mounted on a platform or guide way 36 disposed beneath an elongated chamber or receptacle 37 which extends upwardly to the top of the casing 1 and contains the articles to be vended. This receptacle or container 37, as shown, is rectangular in cross section and is suitably mounted or supported from the walls of the casing 1 by means of brackets, such as 38. It is understood that between each handle member 3 and its container 37 there is a movement transmitting mechanism similar to that described.

A spring 39 extends between each of the blade members 5 and 6 and the platform 10 and tends normally to hold the handle portions 3 in their upward position. The lower end of this spring is connected to a stop member 40 which acts to limit the downward movement of the handle 3 while the spring 39 is being compressed. The lever section 27 is connected by a spring 41 to the casing 1. This spring tends to restore the lever section 31 to the position shown in Fig. 1.

As viewed particularly in Figs. 4, 5 and 6,

the package or article-ejecting apparatus is disposed beneath the ends of the receptacles 37. The ejecting member 35 is adapted to be reciprocated backward and forward on the shelf 36, and at its rear end is provided with a depending flange portion 42 which limits the forward movement of the member 35 as it contacts against the rear edge of the shelf 36. This flange 42 also limits the rearward movement of the member 35 as it contacts with the abutment 43 shown in Fig. 2 and mounted on a platform or shelf 10. A spring 44 is connected beneath the shelf 36 at one end to a front wall 45 of the platform 10 and at the other end to the flange 42. Pins 46 and 47 are connected to the flange 42 and the wall 45, respectively, and are surrounded by the adjacent convolutions of the spring 44. This spring tends to keep the ejecting member 35 in a forward position.

As shown particularly in Figs. 4, 5 and 6, there are disposed between the plurality of article-ejecting members 35, and mounted on the shelf or platform 10, a plurality of bars 48. Each bar is provided along opposite edges with a horizontal flat surface 49 and a vertical wall 50. On each surface 49 a bar or plate 51 is rigidly disposed and connected thereto in any suitable manner. This plate 51 is provided with a plurality of notched portions, such as 52. On the vertical wall 50 above the notched plate 51 is disposed a curved cam plate 53, the forward end 54 of which extends downwardly into close contact with the front end of the plate 51. As shown in Fig. 4, the ejector member 35 has been withdrawn to the full rearward limit of its travel. This ejector member is provided with a transverse slot 55 which extends through the member and has considerable depth. In this slot a long pin 56 is disposed, the ends of the pin adapted to extend beyond the member 35 and to co-operate in the manner hereinafter to be described with the plates 51 and 53. In Fig. 4 the pin 56 is disposed in the rear notch of the plate 51, preventing further rearward movement of the member 35. In Fig. 5 the pin 56 has moved forward with the casing 35 and has passed beneath the front flexible end of the cam plate 53. It will be understood that whenever the ejector casing 35 is withdrawn to the position shown in Fig. 4, an article to be vended, such as 57, will drop down by gravity on to the platform or shelf 36 ready to be pushed therefrom by the casing 35. As the package 57 is ejected from the platform 36, it drops on to a sloping plate 58 which extends downwardly toward the front of the casing 1, where the article can be removed by the person manipulating the device.

It will be understood, of course, that in connection with each ejector casing 35 there are two sets of plates, such as 51 and 53,

each set co-operating with the end of the pin 56 which is connected with each ejector casing 35.

In the operation of this machine, it is first necessary that a coin be inserted in each of the chutes 23 related with any particular handle. There are two chutes for each handle to be operated, one chute connected to the passage through which the blade 5 moves, and the other chute connected to the 75 passageway through which the blade 6 moves. It will also be apparent that unless a coin is in each chute, the blade in the passage in which there is no coin will contact with the projections 21 and that further movement of the handle will be prevented. Therefore, it is only when coins are in all of the chutes connected to any particular handle that these handles can be moved beyond a predetermined amount.

When the coins are properly disposed in all the chutes or passageways, then the handle, by being moved down, will move the coin to force the flexible plates backward, and by so doing withdraw the projections 21 from the line of travel of the blades so that the handle can be moved downward. This downward movement will proceed until the blade portions contact with the stops 40. As the handle portion is moved downward, the linkage previously mentioned will cause the retraction of the ejector casing 35 connected to that particular handle portion, and as soon as this casing is retracted a sufficient distance, another article will drop down on to the platform 36. In this retracted position of the ejector member, however, the spring 44 is under considerable tension. The spring 41 is also extended and spring 39 is under considerable compression; consequently, when the handle 3 is released these springs will cause the quick forward movement of the ejector casing 35 which moves the article 57 off from the platform 36 and on to the curved plate 58. The article will then slide down this curved plate to the front of the casing, where it can be removed by the operator.

In order to further understand the operation of the means whereby only one article can be removed or ejected upon the insertion of a definite number of coins, we will assume that the ejector casing has been turned back into the position shown in Fig. 4, in which circumstance an article 57 is in the full line position shown in Fig. 4, on the platform or shelf 36. Assuming in addition that the handle 3 is allowed to retract sufficiently far to move an article to the dotted position shown in Fig. 4, it may well be that in this dotted position the article might by gravity fall off the platform and slide down the plate 58 without any further movement of the casing 35. If this were the case, then it might be possible for the operator imme-

diately to move the handle down again, whereupon another article would drop on to the shelf 36 and a similar procedure could ensue, whereupon the operator would be enabled to get out a great many articles by paying only a given initial sum. It is, of course, assumed that he does not permit the elevation of the handle to a point above the normal position of the projections 21.

10 To overcome this difficulty, I have provided the plates 51 and 53 previously mentioned. It will be seen that whenever the ejector casing 35, in moving forward a distance not quite sufficient to force the pin 56 under the end 54 of the cam plate 53, that any backward or retractive movement of the casing 35 will result in the pin 56 engaging in one of the notches in the plate 51, whereby further retractive movement of 15 the casing 35 is prevented. Furthermore, it will be seen that from the beginning of the forward movement of the casing 35 from the position shown in full lines in Fig. 4, the pin will ride over the notched 20 portions of the plate 51 and alternately will lie in a position to engage with one or the other of these notched portions. If, however, the member 35 is moved forward a sufficient distance, as indicated in full lines 25 in Fig. 5, so that the pin 56 will have been forced under the end 54 of the cam plate 53, then a retractive movement of the casing 35 will permit the pin 56 to ride up on the plate 53 until it drops off the 30 rear end of the plate into the rearmost notched portion, such as 52 of the plate 51. It is, however, predetermined that in order to move the casing 35 forward a distance sufficient to force the pin 56 under 35 the end 54 of the plate 53, the handle 3 must have been moved forward a sufficient distance to cause the blades 5 and 6 to reach a point above the projections 21. Consequently, a downward movement of the 40 handle thereafter is not permitted until additional coins have been inserted.

It will thus be seen that I have provided a device in which by moving a member or handle in one direction an ejector device is 45 retracted to permit an article to move in a position to be ejected. Upon the release of the handle, resilient means such as springs cause the operative movement of the ejector casing to eject the article on to a delivery plate and also the return of the operating handle to normal. It will also be seen that I have provided simple and efficient means whereby the ejection of more than one ar-

50 ticle for a definite amount of money cannot take place, and that excepting for the insertion of the coins and the manipulation of the handle in one direction, the device is entirely automatic.

55 What I claim is:

1. A coin-controlled mechanism for vending machines, which comprises a plurality of flexible plates forming a passageway for a coin, a lever adapted to move in said passageway, means on said plates to support a coin inserted into said passageway, and means on said plates to limit the movement of the lever, said lever adapted to be moved to contact with the coin and spread said plates apart by reason of the engagement of the coin with the supporting means, whereby the lever-limiting means are moved out of the path of the lever so that the coin and the lever may move further downward along the passageway.

60 2. A coin-controlled mechanism for vending machines, which comprises a plurality of flexible plates disposed to form a passageway for a coin therebetween, a projecting surface on certain of said plates adapted to lie in the path of the coin to support the same, and a projecting surface on certain other of said plates to lie in the path of movement of the lever and restrain the same, said flexible plates being fastened together, said coin, when in the passageway and engaged by said lever, adapted by reason of its engagement with the supporting surface to force the plates apart, whereby the lever-limiting projections are withdrawn from the line of travel of the lever to permit its further downward movement.

65 3. A coin-controlled mechanism for vending machines, which comprises a plurality of sets of plates, each set forming a passageway for a coin, an operating handle of the vending machine having a plurality of blades, each blade disposed in one of said passageways, projections on certain of said plates to support a coin when inserted in the passageway, and projections on another of said plates to limit the movement of the blade disposed in said passageway, each of said coins when supported in its passageway and engaged by its respective blade adapted to spread the plates, whereby the blade obstructing surface is moved out of the line of movement of the blade to permit its further downward movement whereby the operation of the vending machine can be completed.

100 105 110 FRANCIS FERDINAND MOLLOY.
